UNITED STATES PATENT OFFICE.

WALTER N. NICHOLLS AND ALEXANDER W. CARMICHAEL, OF TORONTO, ONTARIO,
CANADA.

FASTENER FOR SHEET ROOFING MATERIAL.

1,076,639.

Specification of Letters Patent. Patented Oct. 21, 1913.

Application filed December 23, 1911. Serial No. 667,566.

To all whom it may concern:

Be it known that we, WALTER NELSON NICHOLLS and ALEXANDER WILLIAM CARMICHAEL, both subjects of the King of Great Britain, residents of the city of Toronto, county of York, Province of Ontario, in the Dominion of Canada, have invented certain new and useful Improvements in Fasteners for Sheet Roofing Material; and we do hereby declare that the following is a clear, full, and exact description of the same.

The invention relates to improvements in fasteners for sheet-roofing material, as described in the following specification and illustrated in the accompanying drawings that form part of the same.

The invention consists essentially in the novel formation of strips of sheet metal whereby the joints of the roofing are held securely in a weather tight joint.

The objects of the invention are, to eliminate the use of cement in securing the joints of tar or asphaltum sheet roofing, to hold the edges of the roofing material securely, protecting the lifting or tearing action of the wind, and to devise a simple form of fastener which may be very easily and quickly applied and which will make an effective weather tight joint and may be used on either flat or pitched roofs.

In the drawings, Figure 1 is a sectional perspective view of a portion of a roof showing the application of the invention. Fig. 2 is a perspective view showing the application of the device to a patched roof. Fig. 3 is a perspective detail of an end cap for use at the end of a run of the fasteners. Fig. 4 is an underside plan view of the end cap.

Like numerals of reference indicate corresponding parts in each figure.

Referring to the drawings, 1 is the improved fastener, formed of a length of sheet metal rolled or stamped with the arched ribs 2 and 3 at each of the edges, and having a stepped offset 4 arranged in the flat portion 5 between the ribs. The stepped portion 4 is of a suitable depth to accommodate the edge 6 of the overlapping sheets of roofing material 7.

In the use of this device, the layers of roofing material are preferably laid with the edges overlapping and the fasteners are laid with the offset 4 abutting the edge and they are then secured by inserting the nails 55 8 into the nail holes 9 punched in the crown of the arched ribs 2 and 3 and driven down tight. As the edges of the metal strips are turned downwardly, the driving home of the nails sinks the said edges into the roofing 60 material, thereby making a secure water tight joint and also protecting the raw edges of the material, which is preferably galvanized iron against corrosion by rust.

The end caps 10 shown in Figs. 3 and 4 65 are formed with crowned ends 11 at one end so as to effectively close the end of a rim of the fasteners thereby making the whole joint of the roofing secure.

The meeting ends of the fasteners are 70 lapped the one over the other and when nailed hold the roofing down in a very secure manner making a thoroughly water tight job without the use of cement and as the edges of the roofing material are thoroughly protected the ravages of the weather 75 cannot lift or tear it.

What we claim as our invention is:—

A fastener for sheet roofing material, comprising, a strip of sheet metal formed with a pair of longitudinal arched ribs extending from end to end thereof and an offset forming a longitudinal step between the ribs, one of said ribs having its outer edge adapted to engage the surface of one layer 80 of the roofing material in a weather tight joint and the outer edge of the other rib engaging the adjacent strip of roofing material, the stepped portion between the ribs 85 completely covering the joint.

Signed at the city of Toronto, county of 90 York, Ontario, Canada, this 4th day of December 1911.

WALTER N. NICHOLLS.
ALEXANDER W. CARMICHAEL.
